SHOE OR SIMILAR ARTICLE

David Evins, New York, N. Y.

Application January 18, 1956, Serial No. 39,833

Term of patent 14 years

(Cl. D7—7)

Fig. 1 is a front perspective view of a shoe or similar article showing my new design.

Fig. 2 is the opposite side of that shown in Fig. 1.

Fig. 3 is a bottom plan view thereof.

Fig. 4 is a side rear perspective view.

The dominant feature of my design resides in the molded sole on the instant design as shown.

I claim:

The ornamental design for a shoe or similar article, substantially as shown and described.
